J. STEVENS

Des. 100,131

RADIO CABINET

Filed April 16, 1936

Inventor:
John Stevens
By J. Clark Stacey Atty.

UNITED STATES PATENT OFFICE

100,131

DESIGN FOR A RADIO CABINET

John Stevens, Chicago, Ill., assignor to Zenith
Radio Corporation, Chicago, Ill., a corporation of Illinois

Application April 16, 1936, Serial No. 62,143

Term of patent 7 years

To all whom it may concern:

Be it known that I, John Stevens, a citizen of the United States, residing at Chicago, in the county of Cook and State of Illinois, have invented a new, original, and ornamental Design for a Radio Cabinet, of which the following is a specification, reference being had to the accompanying drawing, forming part thereof.

The figure is a perspective view of a radio cabinet, showing my new design.

I claim:

The ornamental design for a radio cabinet, as shown.

JOHN STEVENS.
